UNITED STATES PATENT OFFICE.

ATTILIO CONTE, OF BUENOS AIRES, ARGENTINA.

LOCK.

1,376,256.

Specification of Letters Patent. Patented Apr. 26, 1921.

Application filed July 16, 1920. Serial No. 396,738.

To all whom it may concern:

Be it known that I, ATTILIO CONTE, a subject of the King of Italy, residing at No. 1276 Avenida de Mayo, Buenos Aires, 5 Argentina, have invented certain new and useful Improvements in Locks, of which the following is a specification.

This invention relates to certain improvements in locks and has for its object an improved lock operating device which operates in combination with a key provided with radial teeth or projections of variable length, of the well known type, said device being caused to rotate by the action of the only 15 key corresponding to the lock, in a manner similar to other known constructions and so as to operate in turn the latch of the lock.

A further object of the invention is to provide a novel lock operating device of absolutely sure and secret working, and inviolable by picklocks or other similar instruments.

The device substantially consists of a series of strikers mounted within a barrel or cylinder normally locked against rotation by a series of latches or pawls which engage with recesses of the cylinder opposite to the strikers, the pawls being released by said strikers when the corresponding key 25 acts on these latter, while, to the contrary, if the lock should be tampered with by a wrong key, the projecting strikers will cause a second projection or hook on the pawls to engage with a groove of the cylinder, and the strikers which have not been sufficiently raised will hold the first hook of the pawl in engagement. In the former case, if the right key be used, the cylinder 30 will be caused to rotate and will operate the lock, while in the latter case it will remain locked.

In order that the invention may clearly be understood, an embodiment of the same has been shown by way of example in the 45 accompanying semi-diagrammatic drawings, wherein:

Figure 1 illustrates a cross section of a lock operating device in its original or initial position, constructed in accordance with 50 this invention.

Fig. 2 is a longitudinal section of the same.

Figs. 3 to 5 are sectional views which represent several stages of the operation of the 55 locking device. Departing from the initial position shown in Fig. 1, Fig. 3 shows the

key in its second position, with the strikers raised. Fig. 4 illustrates the third position of the parts, in which the cylinder has rotated and operated the lock; Fig. 5 shows 60 the device in a locked position on account of a wrong key being used.

In all the different views, the same numerals of reference indicate like or corresponding parts.

1 is a metallic cylinder or barrel, rotatably mounted in any suitable manner within the lock, not shown in the drawings. Said cylinder is adapted to transfer its motion to the latch of the lock, either by directly 70 operating the same or by releasing said part so as to allow of the same being acted upon by another element. These movements may be performed in any convenient or well known manner, for instance by means of a 75 shaft or handle (not shown) having a squared end which may be fitted in a similarly-shaped hole 2 formed in the cylinder.

3 indicates a series of strikers, arranged within a recess of the cylinder 1, being pivoted to a common epicyclic axle 4. The strikers are separated from each other by means of the washers 5.

In the interior of the cylinder 1, a second concentric cylinder 6 is mounted, provided 85 with a longitudinal slot 7 into which is inserted the key 8. This latter is of the well known type, having radial teeth or projections of the same width, equally spaced and of varying length. To each of the strikers, 90 one of said teeth corresponds, whereby such striker is forced outward as the key is being turned. The inner cylinder is provided with a recess or cut away part 9, into which enter the strikers in their initial position. When turning the key, the teeth slide on the concave profile 10 of the strikers, thereby pushing the same toward the periphery.

11 indicates a series of pawls, in number 100 equal to that of the strikers and arranged opposite to these latter. Said pawls are mounted to oscillate on a common axle 12, secured in any suitable manner within the lock, being spaced from each other by means 105 of the washers 13. The two arms of said pawls are each provided with a hook. One hook, 14, enters into the recess containing the strikers and bears on these latter under the action of a spring 15, suitably secured 110 to the pawl and bearing on a stop 16. The other arm 17 of the pawl may, when oper-

ated, engage in a longitudinal groove 18, formed in the cylinder.

From an inspection of the drawings, the working of the above device will be readily understood. In the initial position shown in Fig. 1, all the pawls enter into the recess containing the strikers, whereby these latter are pushed toward the inner cylinder. When the key is inserted and made to turn 10 a certain amount, as shown in Fig. 3, the teeth of the key will push out the strikers and these latter in turn will push out the pawls. As the heads of the strikers differ in length one from another, in order to be able 15 to operate the lock, it will be necessary that the corresponding teeth of the key be of such a length that each of them will carry the respective striker to the level of the periphery of the outer cylinder or barrel, as 20 clearly shown in Fig. 4. In this case, the pawls will neither engage in the recess of the striker nor in the groove 18. At this moment, on a further turn of the key, the stop 19 of the inner cylinder will carry 25 with it the outer one, which in turn will operate the latch of the lock in any suitable manner.

If the key used is not the right one, owing to even one single tooth being different, the 30 respective pawl will either not be lifted enough or too much and will in both cases always engage with the cylinder, either with the hook 14 or with the hook 17.

In Fig. 5 a case is illustrated in which the 35 tooth is too long for the corresponding striker, which is caused to protrude from the cylinder and causes the hook 17 on the associated pawl to engage with the groove 18.

It will therefore be seen that there is only 40 one instance in which a key will correspond with a combination of strikers, and that such combination may be varied infinitely, so that by this arrangement a really reliable and inviolable lock is obtained.

45 Having now described my said invention and in which manner the same is to be performed, I declare that what I claim as new and desire to secure by Letters Patent, is:

50 1. In locks with keys having radial teeth of variable length a lock operating device which by means of the key causes the operation of the lock in any suitable man-

ner, said device substantially consisting of an outer cylinder provided with a series of strikers, an epicyclic axle whereon the 55 strikers are mounted, the heads of said strikers being of variable length, a series of pawls arranged opposite to said strikers and bearing on the same, hooks formed on said pawls and adapted to lock said outer 60 cylinder against rotation, an inner cylinder concentric with the outer cylinder and provided with a longitudinal slot for the insertion of the key which by its rotation will move the strikers outward and thereby cause 65 them to release the hooks on said pawls from locking engagement with the outer cylinder, the said inner cylinder being provided with a means for imparting rotation to the outer cylinder after the latter has been released 70 from the pawls, substantially as above described and for the purposes set forth.

2. In a key-operated lock, the combination of relatively-movable, concentric inner and outer cylinders, the former of which has a 75 key-receiving slot, a series of strikers carried by the outer cylinder and adapted to be moved outward during the rotation of the inner cylinder by the key, a series of pawls normally engaging the outer cylinder to 80 lock the same against rotation but operable by the strikers, during their outward movement, to release said outer cylinder, and means on the inner cylinder for transmitting its rotary movement to the outer cylinder after the latter has been released from 85 said pawls.

3. In a key-operated lock, the combination of a rotatable cylinder, a series of pawls normally engaging said cylinder to lock it 90 against rotation, and a series of strikers carried by the cylinder and adapted to be moved outward by the key of the lock during the turning movement of the key, said strikers being arranged opposite said pawls 95 so as to bear against them during their outward movement and thereby release the pawls from the cylinder.

In testimony whereof, I hereunto affix my signature in presence of two witnesses.

ATTILIO CONTE.
